(57) **CLAIM**

The ornamental design for a patterned wipe, as shown and described.

DESCRIPTION

FIG. 1 is a top perspective view of a patterned wipe showing our new design;

FIG. 2 is a top plan view of the patterned wipe of FIG. 1; FIG. 3 is a bottom plan view of the patterned wipe of FIG. 1; and,

FIG. 4 is a side view of the patterned wipe of FIG. 1. The dot-dash broken lines indicate the boundary of the claim and form no part thereof.

1 Claim, 3 Drawing Sheets
